ATTORNEY

UNITED STATES PATENT OFFICE.

EMILE JOHN WELFFENS, OF MANCHESTER, ENGLAND.

SWING GEARING FOR SLUBBING, ROVING, AND LIKE FRAMES.

Application filed April 24, 1923. Serial No. 634,248.

To all whom it may concern:

Be it known that I, EMILE JOHN WELFFENS, a subject of the King of the Belgians, residing at 50 Duncan Road, Longsight, 5 Manchester, in the county of Lancaster, England, have invented new and useful Improvements Relating to Swing Gearing for Slubbing, Roving, and like Frames, of which the following is a specification.

10 The invention relates to swing gearing for slubbing, roving and like frames.

It aims at securing renitent lateral constraint in spring loaded swings as described in British Patent No. 130549, at providing 15 easy means for adjusting and maintaining the thrust-arm of such swings in position, and at constructions securing automatic lubrication of the mechanism in an efficient and economical manner.

20 The invention is explained with reference to the accompanying drawings, diagrammatic, but clearly showing the principles involved. Referring to the drawings—

Figure 1 shows a sectional plan, and

25 Figure 2 an elevation of the rail box and the members it carries and contains;

Figure 3 is an elevation and

Figure 4 is a plan showing the thrust-arm, the thrust spring and as much of the 30 spring-bracket as required for elucidation.

Figure 5 is a section through the thrust arm boss upon which the driven chain wheel revolves;

Figure 6 is a development showing the 35 arrangement of oil holes and oil grooves in that boss;

Figure 7 shows the spring used to secure renitent lateral constraint, automatic compensation for lateral wear, oil retention and 40 elimination of chatter;

Figure 8 shows in elevation, and

Figure 9 shows in plan and section plan, the member upon which the thrust-arm rests and slides to and fro;

45 Figure 10 is a partial elevation and

Figure 11 a sectional side view of the driven chain wheel given to show the construction of the jaws which grip the connecting plate.

50 Figure 12 is a side elevation, partly in section, showing the invention applied to

a flier frame, parts being illustrated in dotted lines.

Figure 13 is a plan view of the same.

In Figures 1 and 2, numeral 1 designates 55 the rail box. Spur wheel 2 is fixed to front bobbin shaft 3, that shaft rotating in bearings 4 and 5. Spur wheel 6 rotates in bearing 7 and is fixed to back bobbin shaft 8. The rectangular plate 9 slides in jaws on spur wheel 6 and on chain wheel 10, these jaws engage the plate 9 at 90° and constitute, with the plate, the Oldham coupling that connects wheels 6 and 10 for rotation. Chain wheel 10 rotates on the boss of thrust-arm 11, the boss end of that arm resting and sliding upon member 12. Member 12 forms a bearing for shaft 8 and oscillates in bearing 13. Spring 14 exerts lateral pressure, and is loose around member 12. 60 Multiple drip lubricator 15, with its lid 16 is fixed to rail box 1 by bolt 17, which also fixes rack 18, or in any other suitable manner. Tubes 19, 20 and 21 conduct the lubricant respectively to bearing 5, to spur 65 wheels 2 and 6 and to bearing 13. Needles 22, 23 and 24 in the foregoing tubes, regulate the flow of lubricant.

Having designated the component parts, 70 their action will be explained where relevant. Spring 14 constrains renitently, components 9, 10, 11 and 12, thereby avoiding the rigidity otherwise required to keep them in position. It provides automatic compensation for lateral wear in these components whilst allowing lateral freedom of motion. Its lateral pressure prevents the escape of lubricant whilst creating the slight drag required to avoid chatter when plate 9 becomes easy in the jaws on wheels 6 75 and 10.

The shouldered threaded stud 25, with locking nut 26, screws adjustably in thrust-arm 11 and engages a slot 27 provided in spring bracket 28, see Figures 3 and 4. A 80 central line through the slot 27 coincides with the axis of the driving shaft A and consequently stud 25 remains in a line with the axis of the driving shaft and constitutes an unconstrained center of oscillation 85 for the thrust arm 11. The circular portion of arm 11 engaged by spring 29 is 90 100

slightly taper, thereby spring action forces the arm and consequently the shoulder of stud 25 against bracket 28, and by adjusting stud 25 we may position arm 11 so that the axis of its boss will be maintained parallel or coincident with the axis of shaft 8 during operation whilst avoiding rigid connections between the moving and the stationary parts of the machine.

10 Automatic lubrication obtains in an efficient, waste avoiding manner. External oiling of plate 9 and of the jaws in which it reciprocates is unsatisfactory. The centrifugal action of the mechanism throws the oil. 15 Lubrication effected from the inside harnesses the centrifugal action to further efficiency. Action is as follows:—

(a) *Backshaft*.—Tube 21 conducts oil through bearing 13, through hole 30 in member 12 (see Figures 1 and 8) to chamber 31 (see Figures 1 and 8), and to shaft 8. A groove at the bottom of the bore in 12 conducts the oil from chamber 31 to void created by hollow plate 9 between 6 and 10, 25 and so through grooves 32 to recesses 33 in the jaws on members 6 and 10 (see Figures 1, 2, 9 and 10). Plate 9 and wheels 6 and 10 are so arranged that the oil is retained in all relative positions of 6, 9 and 10, centrifugal 30 action effecting the required distribution.

The movement of alternate vertical translation of box 1 causes relative displacement of jaws 6 and plate 9 with regard to 10, both wheels remaining connected for rotation by plate 9, it oscillates arm 11 and causes that arm to slide to and fro on 12 and it oscillates 12 in 13. The needle 24 provided in 12 (see Figures 1, 7 and 8) allows the oil to run in the oil well 35 of boss on arm 11 (see Figure 40 5) when oscillation inclines 12 in either direction. Well 35 is kept closed by member 12 (see Figures 1, 7 and 8). From that well the bearing of wheel 10 is lubricated through lower holes and groove in jaws of arm 11 45 shown developed in Figure 6, the oil returning to the well through upper holes. Any surplus of lubricant in void between 6 and 10 or in well 35 flows from one to the other through hole 43. Holes 36 and 37 (see Figures 1 and 10) conduct, through centrifugal 50 action, part of the oil in bore of wheel 10 to the chain 100, and the chain in its turn lubricates the teeth on both its wheels 10 and 101.

55 Part of the lubricant conducted contacts with shaft 8 provided with a spiral groove 38, that groove conducting the oil through hole 39 in boss of wheel 6 (see Figure 1) to chamber 40 in bearing 7. The presence of oil lubricates shaft 8 and its bearing in 12, and the certain amount of oil thrown through window 34 and in void between wheels 6 and 10 furthers lubrication.

(b) *Front shaft*.—Tube 19 conducts oil to 60 chamber 41 in bearing 5 and the groove in

shaft 3 in its turn conducts oil to chamber 42 in bearing 4, the boss of wheel 2 fitting sufficiently close between 4 and 5 to avoid waste.

(c) *Wheel teeth*.—Tube 20 causes oil to 70 flow on wheels 2 and 6 and so secures lubrication of their teeth.

What I claim as my invention and desire to secure by Letters Patent is:—

1. The combination of a driving member 75 having a fixed horizontal axis of rotation, a thrust arm oscillating on an axis movable in the horizontal plane of the axis of the driving member, a driven member supported by the said arm, flexible means for transmitting motion from the driving member to the driven member, a vertically reciprocating bobbin driving wheel and coupling means connecting the driven wheel with the bobbin driving wheel.

2. The combination of a driving member 80 having a fixed horizontal axis of rotation, a thrust arm oscillating on an axis slidable in the horizontal plane of the axis of the driving member, means for guiding the pivoted end of the thrust arm in its horizontal slidable movement in the plane of the axis of the driving member, a driven member supported by the said arm, flexible means for transmitting motion from the driving member 85 to the driven member, a vertically reciprocating bobbin driving wheel and coupling means connecting the driven wheel with the bobbin driving wheel.

3. The combination of a driving member 90 having a fixed horizontal axis of rotation, a bracket having a horizontal slot arranged in the plane of the axis of the driving member, a spring adjustably mounted on the bracket, an oscillating thrust arm having a pivot operating in the slot of the said bracket, said thrust arm being engaged at its pivoted end by the said spring, a driven member supported by the said arm, flexible means for transmitting motion from the driving member 95 to the driven member, a vertically reciprocating bobbin driving wheel and coupling means connecting the driven wheel with the bobbin driving wheel.

4. The combination of a driving member 100 having a fixed horizontal axis of rotation, a bracket having guiding means arranged in the horizontal plane of the axis of the driving member, a thrust arm having a boss at one end and provided at the other end with 105 a pivot arranged in the said guiding means of the bracket whereby the thrust arm is adapted to oscillate, a driven member mounted on the said boss, flexible means for transmitting motion from the driving member to 110 the driven member, a vertically reciprocating bobbin driving wheel and coupling means connecting the driven wheel with the bobbin driving wheel.

5. The combination of a driving member 115

having a fixed horizontal axis of rotation, a thrust arm having a boss and oscillating on a pivot movable in the plane of the horizontal axis of the driving member, a bearing 5 sleeve carried by the arm, a bobbin shaft having a wheel and mounted in the said sleeve, means for coupling the driven member and the wheel of the bobbin shaft, and a

spring mounted on the said sleeve and arranged to constrain renitently the driven 10 member and the means for coupling the same with the wheel of the bobbin shaft.

In testimony whereof I have signed my name to this specification.

EMILE JOHN WELFFENS.
